UNITED STATES PATENT OFFICE.

FRANK VAN ALSTINE, OF SAN DIEGO, CALIFORNIA.

REINFORCING STRUCTURE FOR MOLDED CASKETS.

Application filed September 21, 1925. Serial No. 57,702.

The invention relates to improvements in the manufacture of burial caskets and analogous devices, of the type which is molded from appropriate plastic, a magnesite composition being preferably used, mixed with 5 chloride. My invention resides in the reenforcing structure for a molded casket and it is my object to provide a structure of this class which may be easily and inexpensively 10 formed, yet will be generally desirable and efficient, said structure being provided with wooden strips which are exposed at the inner side of the completed casket, so that the casket lining may be readily tacked to 15 such strips. The mere use of wooden strips for this purpose is not original with me, but the relation of strips with other parts of the reenforcing structure is novel and it is upon such relation, together with other 20 features of novelty, that I seek patent protection.

Figure 1 is a vertical longitudinal sectional view through the casket reenforcing structure, the top reenforcing means being 25 separated from the reenforcing means for the body of the casket.

Figure 2 is an enlarged detail sectional view showing the construction at the edge of the top-reenforcing structure.

Figure 3 is an enlarged detail vertical section through the construction at the upper portion of the body reenforcement.

Figure 4 is an enlarged detail section through the construction at the lower corners 35 of the body-reenforcing structure.

Figure 5 is a horizontal sectional view as indicated by line 5—5 of Figure 1.

Figures 6 and 7 are perspective views of 40 fragmentary nature, illustrating the preferred manner of forming the bottom, the side walls and the end walls of the body-reenforcing structure, from a single piece of woven wire or equivalent reticulate metal.

Figure 8 is a longitudinal sectional view 45 through a complete casket embodying the improved reenforcing structure.

Figure 9 is a horizontal sectional view as indicated by line 9—9 of Figure 8.

Figure 10 is a vertical transverse sectional view on line 10—10 of Figure 8.

The construction for reenforcing the body of the casket will first be described. This construction includes a bottom 11, a pair of longitudinal side walls 12, and end walls

13, all formed from coarse woven wire or 55 any other desired open work or reticulate metal. In order to form the bottom, side and end walls, a single piece of the reticulate metal is preferably cut substantially as shown in Figure 6, it being understood 60 that while only one end of the sheet is shown, the other end is correspondingly cut. Then, this sheet is bent in the manner shown in Figure 7, so that its portions 11^a, 12^a and 13^a, form the bottom 11, side walls 12 65 and end walls 13 respectively, the lower edges of said portions 13^a being preferably bent inwardly under the ends of the bottom 11, as indicated at 14. The portions 13^a overlap each other to effectively reinforce the end walls, for the attachment of appropriate handles 15, to the completed casket at these points, and if desired, strands of these portions may be interhooked or interlaced with each other.

Upper and lower longitudinal and transverse wooden strips 16 and 17 respectively, are disposed horizontally at the inner sides of the walls 12 and 13, near the upper and lower edges of the latter, said strips and walls being secured together by any preferred means such as the lengths of wire 18. Other longitudinal wooden strips 19 and transverse strips 20 are applied to the upper side of the bottom 11, and may be secured to 85 the latter by wiring as indicated at 21. All of these wooden strips are exposed at the inner side of the casket when completed, and they provide for tacking the casket lining in place.

Vertically disposed strips 22 of reticulate metal, extend between spaced portions of the upper and lower wooden strips 16 and are secured to the latter by wiring 23 or other suitable means. These strips are spaced inwardly from the side walls 12 and they preferably have their edges 24 bent laterally outward into contact with said side walls. The strips 22 form effective reinforcements to which to anchor the handles 25 at the 100 sides of the completed structure.

To reinforce the upper edges of the walls 12 and 13 and to provide for the formation of an external bead or rib on the completed casket, the construction detailed in 105 Figure 3 is provided. In this view and such other views as permit the application of reference characters to these parts, 26

designates a channel-shaped strip of reticulate metal, in whose channel the upper edges of the walls 12 and 13 are received. 27 designates another channel-shaped strip 5 of the same material, disposed at the exterior of the walls 12 and 13, adjacent the lower edge of the strip 26, the channel of this strip being disposed inwardly. Strands 28 on the edges of the strip 27 preferably 10 pass through the reticulate walls 12 and 13 and through the reticulate strip 26, as fully shown in Figure 3. To reenforce the lower corners of the structure and provide for an external rib or bead formation at 15 the lower corners of the completed casket, channel-shaped stripping 29, of reticulate metal, is disposed at the exterior of the structure with its channel facing inwardly, strands 30 at the edges of this stripping being 20 preferably passed through the reticulate side and end walls, this construction being detailed fully in Figure 4.

The reenforcing structure for the top of the casket comprises a skeleton frame 31 25 formed of wooden strips, this frame being provided with a covering 32 of reticulate metal. This covering projects beyond the frame and has its edge portion folded upon itself as indicated at 33, this edge portion being received in the channel of channel-shaped, reticulate, metal stripping 34. This construction effectively reenforces the edge of the covering 32 and provides for the necessary thickened formation at the edge of the casket cover. The wooden frame 31 is exposed at the inner side of the completed 30 cover and the top lining is tacked to it. This frame may be secured to the cover 32 in any suitable manner, for instance by wiring at intervals as indicated at 35.

After the body and top reenforcing structures have been completely formed as above described, or substantially in this manner, they are placed in appropriate molds and 45 the plastic material is poured around them and allowed to set, thus providing a complete casket body B and top T, the two being properly shaped for tight engagement with each other. When the completed 50 top and body are removed from the molds, the linings L and L' may be tacked in place after first performing any other necessary work, such as attaching the handles 15 and 25.

Excellent results are obtainable from the 55 details of construction herein disclosed and they are therefore preferably followed. However within the scope of the invention as claimed, modifications may be made.

60 I claim:—

1. A reenforcing structure for a molded casket, comprising a bottom, side and end walls formed of reticulate metal, upper and lower longitudinal and transverse wooden 65 strips secured to the inner sides of said side

and end walls near the upper and lower edges thereof, providing for tacking the casket lining in place, and vertical strips of reticulate metal extending between the upper and lower longitudinal strips of wood 70 and secured thereto, said metal strips being inwardly spaced from the aforesaid side walls and constituting effective means to which to anchor the casket handles.

2. A structure as specified in claim 1; 75 the vertical edge portions of said metal strips being outwardly bent into contact with said side walls.

3. A reenforcing structure for a molded casket, comprising a bottom, side and end 80 walls formed of reticulate metal, and channel-shaped stripping of reticulate metal disposed at the exterior of said side and end walls, the open sides of the channels being disposed inwardly toward the walls, said 85 stripping forming reenforcement for an external rib or bead formation on the casket.

4. A structure as specified in claim 3; 90 said stripping having strands at its edges passing through said reticulate walls.

5. A reenforcing structure for a molded casket, comprising a bottom, side and end 95 walls formed of reticulate metal, and channel-shaped stripping of reticulate metal into whose channel the upper edges of said side and end walls project, said stripping having its sides terminating a short distance below said upper edges of said side and end walls and forming effective reenforcement 100 for the upper edges of the casket.

6. A reenforcing structure for a molded casket, comprising a bottom, side and end 105 walls formed of reticulate metal, channel-shaped stripping of reticulate metal into whose channel the upper edges of said side and end walls project, and other channel-shaped stripping of reticulate metal at the exterior of said walls adjacent the lower 110 edge of the first named stripping, said other stripping having strands at its edges passing through the reticulate walls and through the first named stripping, all of said stripping forming reenforcement for the upper edge portion of the casket. 115

7. A reenforcing structure for a molded casket top, comprising a skeleton frame of wood to which to tack the top lining of the casket, a covering of reticulate metal over 120 said frame and projecting beyond the same and channel-shaped stripping of reticulate metal into whose channel the edges of said covering project.

8. A reenforcing structure for a molded casket top, comprising a skeleton frame of 125 wood to which to tack the top lining of the casket, a covering of reticulate metal over said frame and projecting beyond the same, the edge of said covering being folded upon itself, and channel-shaped reticulate metal 130

stripping in whose channel said folded edge is received.

9. A casket reenforcement including a reticulate metal sheet having a free edge, and a narrow channel-shaped reticulate metal strip into whose channel said edge projects, the sides of said strip terminating

a short distance inwardly from said free edge of the metal sheet to provide a supplemental reenforcement for a thickened ¹⁰ formation at the edges of the casket.

In testimony whereof I have hereunto affixed my signature.

FRANK VAN ALSTINE.
